UNITED STATES PATENT OFFICE.

FRANK M. FAIRCHILD, OF WEST DERBY, VERMONT.

BENCH-DOG.

SPECIFICATION forming part of Letters Patent No. 351,755, dated November 2, 1886.

Application filed June 11, 1886. Serial No. 201,859. (No model.)

To all whom it may concern:

Be it known that I, FRANK M. FAIRCHILD, a citizen of the United States, residing at West Derby, in the county of Orleans and State of Vermont, have invented a new and useful Improvement in Bench-Dogs, of which the following is a specification.

My invention relates to improvements in bench-dogs; and it consists of the peculiar combination and novel construction and arrangement of the various parts for service, substantially as hereinafter fully set forth, and particularly pointed out in the claims.

The object of my invention is to provide novel means for securely and rigidly holding a board or plank in its proper position and against movement on a joiner's or workman's bench while the board is being operated upon in various ways; to provide means which can be easily and readily applied to a bench of any width and construction; and, finally, to provide a device which can be adjusted to engage with the work simultaneously with its application to the bench.

In the accompanying drawings, which illustrate a bench-dog embodying my invention, Figure 1 is a perspective view. Fig. 2 is a longitudinal sectional view through the device. Fig. 3 is a detached perspective view 30 of the holding-arms, and Fig. 4 is a view of the device applied or adjusted for use upon a bench, a portion only of the latter being shown.

Referring to the drawings, in which like letters of reference denote corresponding parts in all the figures, A designates the lever, and B and C the holding-arms that are carried and actuated by the lever, of a bench-dog embodying or constituting my invention.

One end of the lever A is slotted longitudinally, as at a, for a considerable distance, and in this slot works or slides a pin or screw, b, that is connected with or secured in the arm B of the device.

The arm B is provided at one end with the hook-shaped claw b', which is slotted or bifurcated, as shown, and this claw is formed in one piece with the holding-arm, and is adapted to take or fit over the upper edge of the bench and be forced into the latter by the action of 50 the lever, as will be presently described.

The arm C comprises the two end sections, c, which are arranged out of line with each

other and connected by an integral intermediate portion, c', which forms the shoulders c", one of the said shoulders having the 55 curved and recessed edge, as shown. One end of the arm C is pivoted to and carried by the lever by means of a pin, screw, or other like means, which passes through the slots d and d' of the lever A and arm C, respectively, and the opposite end of the said arm C is provided with a hook-shaped claw, e, which is formed integral therewith and is similar in form to the claw of the arm B, as shown. The claw C is further provided on 65 one of its edges with a projecting pin or detent, F, that is rigidly secured thereto by screws, or formed integral therewith, which is adapted to be forced into the end of the board or other work and hold it rigidly in place while 70 it is being operated upon.

G designates a stop pin or screw, which is affixed or screwed to the lever A near one end, and it is arranged in the path of the recessed shoulder c" of the swinging arm C, so that the 75 movement of arm C is limited in one direction by the said shoulder c" coming in contact therewith, the pin entering the recess of the shoulder.

The operation of my invention is as follows: 80 To adjust the dog upon a bench for use, the claws of the holding-arms are fitted over the edges of the bench and the arms are moved on their pivots intermediate of the lever A and the arms. The arms are adjusted longitudinally of the lever, in the slots thereof, if necessary, to adapt them to fit a bench, and the arms are arranged out of line with and to one side of the lever. After the board has been placed on the bench the lever is moved toward 90 the arms to force the claws of the latter into firm engagement with the bench and bring the stop-pin G, carried thereby, near its lower free end into the recess of the shoulder c" of the arm C. The lever A is grasped by the hand at 95 its lower free end and forced toward the arm C, at one end thereof, and the lever moves on the pivots of the said arms B and C to actuate the latter. The movement of the lever in one direction is limited by the stop-pin G 100 coming in contact with the recessed shoulder of the arm C, and the detent of the said arm is forced into the end of the plank to hold the latter in place and against accidental move-

ment or displacement. The reverse or retro-grade movement of the lever releases the holding-arms from the bench and the detent from the work, which can then be removed.

5 It will be seen that the claws of the holding-arms enter the bench and prevent movement of the arms and the displacement thereof, and the parts are very simple and strong in their construction, as well as durable, and 10 cheap and inexpensive of manufacture.

Having thus fully described my invention, what I claim as new, and desire to secure by Letters Patent, is—

1. In a bench-dog, the combination of a lever, an arm, B, connected to one end of the lever, and having a claw at one end arranged to engage the end of the table, an arm, C, connected to the lever intermediate of its ends, and also provided with a claw to engage the 15 table, and a detent, F, affixed to the arm C near its free end and projecting beyond one side of the same, substantially as described, for the purpose set forth.

2. In a bench-dog, the combination of a lever, an arm, B, connected to one end of the lever, and having a claw arranged to engage 20

the end of the table, an arm, C, also connected to the lever near its middle, and having a claw at its free end to engage the table, and a recessed shoulder near the middle, a stop affixed to the lever, arranged in the path of the shoulder on the arm C, and a detent affixed to the latter arm, substantially as described, for the purpose set forth.

3. In a bench-dog, the combination of a lever having a longitudinal slot, a, at one end, and a similar shorter slot, d, near its middle, the arms having the claws to engage the ends of the table, the pins passing through the slots of the lever and secured in the arms to connect the same to the lever, and a detent, F, projecting beyond one edge of one of the arms, substantially as described, for the purpose set forth.

In testimony that I claim the foregoing as my own I have hereto affixed my signature in presence of two witnesses.

FRANK M. FAIRCHILD.
